VERNER F. DAVIS, OF ORANGE, NEW JERSEY.

TEMPERATURE-REGULATOR.

No. 873,028.

Specification of Letters Patent.

Patented Dec. 10, 1907.

Application filed November 21, 1906, Serial No. 344,360.

To all whom it may concern:

Be it known that I, VERNER F. DAVIS, a citizen of the United States, residing at Orange, in the county of Essex and State of New Jersey, have invented certain new and useful Improvements in Temperature-Regulators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improved regulator for controlling the temperature in its vicinity, and is of the class that is adapted to be connected with a compressed air system to regulate the admission of the air to a diaphragm valve, the diaphragm valve, in these systems, being held normally open by means of a spring, and closed by the compressed air. This valve is old, and the invention lies in the improved regulator for the air control.

The invention is designed to provide a regulator, of this class, that has a spring actuated valve to be normally closed, the valve being opened, by the contraction of the regulator, to admit air to a casing to actuate a piston to cut off the air supply to allow the spring closing of the diaphragm valve.

The invention is illustrated in the accompanying drawings, in which

Figure 1 is a central vertical section of the regulator. Fig. 2 is a bottom view of the same, and Fig. 3 is a section of the lower part of the regulator taken at a right-angle to the section in Fig. 1.

The device consists of a casing 10 which has an enlarged upper portion 11, and on the upper portion is screwed a cover or top 12 which has, on the top thereof, a boss 13 in which is suitably secured a tube 14 which furnishes the expanding member, being made of a metal susceptible to slight temperature changes. In the top of the expanding member 14 is a block 15, and this is surmounted by a usual stuffing box construction 16, and working in the stuffing box and fitting in a screw-threaded perforation in the block 15, is a rod 17, this being turned by a suitable hand piece 18 which can be graduated, on its outside, to indicate its regulation. Longitudinally arranged in the rod 17 is a perforation 19 which extends from one end of the rod to the other, and it has a suitable tapered por-

tion which fits in the recessed end 20 of a non-expanding bar 21, this bar being provided, near its upper end, with a collar 22 which acts as a guide to assist in holding the bar 21 central, and it is steadily held by means of a light spring 23. The lower end of the bar 21 furnishes a recessed portion 22^a that receives the pointed end of a tapered valve 23^a, which is seated in the valve seat 24 by means of a spring 25 which is stronger than the spring 23 at the top of the bar 21. A plug 26 is inserted underneath the spring 25 to give it a bearing. It will be seen when the spring 25 forces the valve 23^a shut, it prevents compressed air passing from the duct 27, which in turn is fed by the tube 28 which is connected, at its lower end, with the passage 29, this passage receiving the air, from a port 30, which is led in through the inlet port 31. A central passage 32 also leads from the passage 30 for purposes, as will be described hereinafter.

When the temperature in a room gets lower than desired, and the apparatus has been regulated properly, the tube 14 will contract, the rod 17 will press down on the bar 21, which in turn will press down on a valve 23^a and open it against the pressure of the spring 25. The air can now pass through from the passage 27, and it then passes down from the tube 14 into a passage 33, and acts on the top of the piston 34, and forces the piston down. This piston is on one end of a piston rod 35, the other end holding a second piston 36, and the pistons are allowed to go down by reason of an exhaust 37, connecting with the atmosphere, and which allows no back pressure against the piston 34, and this piston 34 being much larger in area than the piston 36, the pistons are readily forced downward. Prior to this downward forcing, the air coming in through the inlet 31 and the passage 30, and passing up through the passage 32, communicates directly and passes out through the outlet passage 38, connected with the outlet port 39, the outlet port 39 being connected, as usual in these systems, with a damper regulator, and when the pistons go down, the piston 36 cuts off the port 38, passes down beyond it, and the air in the diaphragm valve and in the passage 38, is then in communication, through the cylindrical casing, with the outlet 37 and is thus vented to take the pressure off the diaphragm valve and permit it to open to allow the entrance of a heating medium. After the mechanism is in

the position described, and the temperature goes up, the tube 14 will expand, and the pressure is thus relieved from the spring 25 by reason of the bar 21 being allowed to rise, 5 and the valve 23 shuts, closing off the air that was entering through the passage 27. As the expansion of the tube 14 continues, the spring 23 keeps the bar 21 seated on the valve 23^a, but the end 20 of the rod 17 is 10 carried up, and the air in the tube 14 is vented into the atmosphere which takes the pressure off the top of the piston 34, by reason of the air, above the piston, passing out through the duct 33, and the air going in at 15 the bottom of the casing, through the passage 32, forces the pistons up, and there is again direct communication between the inlet passage 30 and the outlet 38, and the diaphragm valve, hereinbefore described, is 20 shut. In the construction of the pistons, I prefer to form them from one piece of metal, round, to fit tightly inside the casing, and they are provided with a circumferential groove 39 to form two bearing surfaces on 25 each piston. The pistons are secured, by shrinking or brazing, to the piston rod 35, and are moved down far enough on the end of the piston rod to allow the end 40, on each end of the rod, to engage the end of the casing, 30 in each direction, to keep the end of the piston from being strained by being forced against the ends of the casing.

These regulators can be adapted for ventilation systems to govern the outlet of air, 35 and the inlet of the same, and can also be used in systems of refrigeration, the application of them being obvious.

Having thus described my invention, what I claim is:—

40 1. A temperature regulator comprising a casing, a hollow expanding member, the casing having an inlet connected by a duct at the top to the expanding member, and a passage at the bottom, a valve actuated by the 45 expanding member and adapted to normally close the duct, a valve on the top of the expanding member, means for the opening of the valve on the expanding member after the valve on the duct is closed, the casing having an air outlet below the pistons and an exhaust between the pistons, and pistons actuated by the air pressure to control the direction of the air.

2. A temperature regulator comprising a 50 casing having an air inlet connected by a duct to an expanding member an air outlet and an exhaust, pistons in the casing, a spring actuated valve normally shut to close

the duct, a hollow expanding member to open the valve, and a valve at the top of the 60 expanding member to be opened after the first valve is shut.

3. A temperature regulator comprising a casing having an air passage at the top for admitting air connected with an air duct at 65 the top, pistons in the casing, the casing having an outlet and an exhaust, a valve to close the air duct, a hollow expanding member connected with the duct and having a passage leading from its interior to the interior 70 of the casing, a rod in the hollow member to open the valve when the expanding member contracts, and a valve in the top of the expanding member adapted to open after the 75 first valve is closed.

4. A temperature regulator comprising a casing having an air inlet opening by a passage into the bottom, and having an air duct opening into an expanding member and having an air outlet near the bottom, the casing 80 also having an exhaust, a piston in the top of the casing, a piston to pass across the air outlet, a rod common to the pistons, a hollow expanding member on the casing, the casing having a passage to the hollow member, a 85 valve in the top of the casing, a spring to close the valve to shut off the duct, a rod actuated by the expanding member to open the valve; and a valve in the top of the expanding member to be opened by the rod 90 after the first valve is shut.

5. A temperature regulator comprising a casing having pistons therein, the casing having an air passage for admitting air and having an outlet, a hollow expanding member, the casing having an air duct leading from the inlet passage to the expanding member, the casing having a passage leading from its interior to the expanding member, a valve closing the duct, a spring to close the 100 valve, a rod resting on the valve, a collar on the rod fitting loosely in the member, a spring between the end of the member and the collar on the rod, and a second rod having a longitudinal perforation adapted to 105 have its lower end seated on the first rod and opening on the other end into the atmosphere.

In testimony, that I claim the foregoing, I have hereunto set my hand this 19th day of November 1906.
